SIGNALING SYSTEM

Filed Jan. 6, 1923

Inventor:
Joseph W. Horton

by W. Griggs Atty.

UNITED STATES PATENT OFFICE.

JOSEPH W. HORTON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed January 6, 1923. Serial No. 610,976.

To all whom it may concern:

Be it known that I, JOSEPH W. HORTON, a citizen of the United States, residing at Bloomfield, in the county of Essex, State 5 of New Jersey, have invented certain new and useful Improvements in Signaling Systems, of which the following is a full, clear, concise, and exact description.

This invention relates to a carrier current 10 system, and more particularly to a carrier current telephone system.

Among the objects of the invention is to produce such a system wherein the usual ringing, supervisory and other signals incident 15 to the establishing of a connection between subscribers are efficiently transmitted without impairing the speech transmission efficiency thereof.

A high frequency carrier current telephone channel is ordinarily coupled to a low frequency line over which low frequency 20 signaling currents and audio frequency currents are transmitted.

The low frequency signaling currents are 25 ordinarily translated into currents of higher frequency for modulating the carrier currents, and the modulated carrier currents are transmitted over the carrier channel.

In order that a carrier current telephone 30 system may be most efficient, the apparatus thereof is designed for carrier currents modulated by audio frequency currents.

Therefore, to attain an object of this invention the modulating signaling currents 35 are of audio frequency.

In accordance with a feature of this invention balanced modulators and demodulators are employed in the transmitting and receiving channels respectively of a carrier current telephone system and two signaling currents of different audio frequencies are employed to modulate the carrier current.

These modulating signaling currents are 45 simultaneously impressed upon the modulator.

The transmitted carrier currents modulated in accordance with such audio frequency signaling currents upon being received are demodulated by the balanced demodulator.

A combination, such as the difference frequency currents, of the audio frequency modulating currents produced by the demodulator is utilized to control the appli-

cation of low frequency signaling current 55 to the low frequency line.

Modulating signaling current of frequencies other than audio frequencies may, of course, be employed.

The invention will be described as applied 60 to a multiplex carrier current telephone system employing guided carrier waves, although it will be understood that it is also applicable to such a system employing unguided carrier waves, as well as to a carrier current telegraph or other system.

The drawing illustrates diagrammatically only so much of a multiplex carrier current telephone system as is necessary for an understanding of the invention.

The apparatus and circuits illustrated are located at the junction between a line L over which low frequency oscillations are to be transmitted, and a line ML over which modulated high frequency oscillations are to be 75 transmitted.

The low frequency line L, according to the customary practice, may extend to and terminate at a telephone switchboard.

The high frequency line ML extends to a 80 distant junction (not shown) between such line and another low frequency line similar to L, at which distance junction apparatus and circuits similar to those illustrated are provided.

The low frequency and high frequency lines L and ML are connected by an outgoing high frequency transmitting channel 85 TL, an incoming high frequency receiving channel RL₁ and a high frequency transmitting and receiving line TRL common to the several channels TL, RL₁ and TL₂, RL₃ of the multiplex carrier current system.

The high frequency transmitting and receiving channels TL and RL₁ are associated 95 with the low frequency line L through transformer 1.

The two channels TL and RL₁ are rendered substantially conjugate by the provision of an artificial line or net AL to balance the line L.

The line TRL, common to the several transmitting and receiving channels, is inductively coupled to the main line ML through a transformer 2.

The main line ML may, of course, be utilized for the transmission of audio or lower frequency oscillations, high pass and low

pass filters being provided, as shown, to separate the audio and ultra audio frequency oscillations.

The outgoing or transmitting channel TL 5 includes a modulator M and a band filter TBF.

The modulator M may be of any well-known type, but, as illustrated, is of the balanced type disclosed in U. S. Patent No. 10 1,343,307, issued June 15, 1920 to John R. Carson.

Carrier currents of the frequency assigned to the channel are supplied to the modulator M from a carrier current 15 source CS.

Currents of modulating frequency are supplied to the modulator through the transformer 3.

The modulator is so organized that carrier currents are not transmitted thereby unless unbalanced when modulating oscillations are impressed thereon.

The band filter TBF is of the general type disclosed in U. S. patents to George A. 25 Campbell Nos. 1,227,113 and 1,227,114, dated May 22, 1917. It is designed to pass only currents of frequencies within either the upper or lower side band and to suppress currents of all other frequencies.

The incoming or receiving channel RL 30 includes a band filter RBF₁ similar to the band filter TBF, a demodulator DM₁, and a low pass filter LPF₁.

The demodulator DM₁ may be of any 35 well-known type but, as illustrated, is of the balanced type disclosed in U. S. patent to John R. Carson, No. 1,343,308, issued June 15, 1920.

Such a balanced demodulator operates 40 upon the homodyne method of receiving and is, therefore, supplied from the circuit 4 with oscillations of the carrier frequency assigned to the channel.

The oscillations supplied from the circuit 45 react in a well-known manner with the received modulated oscillations to detect the low frequency modulating currents.

The low pass filter, which may be of the type disclosed in the Campbell patents hereinbefore referred to, permits the passage of 50 the currents of the modulating frequencies but suppresses currents of higher frequencies.

The system thus far described is a carrier 55 current telephone system of the usual type which functions in a manner well understood by those skilled in the art.

It is customary to ring over low frequency 60 telephone lines, such as L, currents of low frequency such as, for example, 16 cycle currents ordinarily being employed.

Such low frequency currents are not as suitable for modulating the carrier currents as currents of higher frequency.

65 Hence it is usual, as illustrated in U. S.

patent to Aeffel and Davidson, No. 1,402,202, January 3, 1922, to provide at the junction between the low frequency line and the carrier system apparatus controlled by such low frequency currents which in turn controls the application of higher frequency modulating currents to the carrier system. 70

The low frequency line L is, therefore, provided with a ringing response relay 5, which through a relay 12, controls the application of modulating oscillations to the modulator M. 75

The modulating oscillations are two currents of different audio frequencies f_1 and f_2 supplied over a line 6. 80

The source of the two currents of different audio frequencies may be common to the several channels of the system.

A particular advantage of the use of 85 modulating currents of audio frequencies for signaling purposes in a carrier telephone system is that no special intermediate apparatus need be provided in the high frequency line or in the path of carrier currents modulated in accordance with speech 90 frequencies.

Another advantage is that closer frequency spacing of the several carrier channels may be employed whereby a greater 95 number of channels may be provided within a given frequency range.

In order to provide for the necessary 100 translation of ringing currents from main line ML to line L, a rectifier R is associated with the demodulator DM₁ to rectify a combination of the modulating currents. The rectified currents cause the operation of a relay 7 which controls the operation of relay 8 to apply sixteen cycle ringing current 105 to line L.

The input circuit of rectifier R is inductively coupled through a transformer 9 to the common branch of the output circuits of the demodulator DM₁.

The common branch of the demodulator 110 output circuits includes the transformer primary and a condenser 10, which cooperate to tune the common branch to a combination component of the modulating currents, preferably, that of their difference frequency. 115

The common branch is in balanced relation to the circuit traversed by speech currents, so making it sharply resonant to the difference frequency wave of the received 120 line currents has no disturbing effect upon the transmission of the speech currents.

The input circuit of the rectifier R is also tuned to such difference frequency currents through the provision of a condenser 11 to 125 cooperate with the transformer secondary windings.

The operation of the ringing feature of the system will now be described.

130 Sixteen cycle ringing current incoming

from the line L actuates ringing response relay 5 which opens the circuit of relay 12. Relay 12, in releasing its armatures, applies the two modulating currents of different 5 audio frequencies f_1 and f_2 from the circuit 6 to the input of the modulator M. The modulating currents so applied modulate the carrier current from the source CS, the balanced modulator operating to eliminate 10 the unmodulated carrier component. The modulated carrier currents are then transmitted to the band filter TBF which suppresses one of the side bands. The other side band is transmitted over the common 15 transmitting and receiving line TRL and through the transformer 2 to the main line ML.

Carrier currents modulated in accordance with the two currents of audio frequencies 20 f_1 and f_2 incoming from the line ML are transmitted into the common circuit TRL and are selected by the filter RBF₁. The modulated carrier currents transmitted through the filter RBF₁ are impressed upon the input circuit of the balanced demodulator DM₁ where they react with the unmodulated carrier current supplied from circuit 4, and also with each other. Currents resulting from the interaction 25 of the received line currents with the unmodulated carrier current are of the frequencies f_1 and f_2 . Such currents of these frequencies are balanced out in the common branch of the demodulator output circuit, 30 but are impressed upon the low frequency output circuit RL₁. The interaction between the two components of the received line currents results in currents of frequencies f_1+f_2 and f_1-f_2 which appear in the common branch but not in the low frequency output circuit RL₁ since they are balanced out in the output transformer. Since this common branch is tuned to the difference frequency currents of the received line currents, 40 the difference frequency currents are transmitted through the transformer 9 and are impressed upon the input circuit of the rectifier R. Relay 7 responds to the rectified currents and causes the operation of relays 8 and 13. Relay 8 disconnects ringing response relay 5 from the line L and connects thereto 16-cycle ringing current. Relay 13, in operating, short-circuits the primary windings of transformer 3, thus preventing interference during the application 45 of 16-cycle ringing current to the line L.

The invention set forth herein is, of course, susceptible of various other embodiments and adaptations.

60 The invention claimed is:

1. In a signaling system, means for transmitting a carrier wave modulated by oscillations of a plurality of different frequencies, a balanced demodulator having output circuits provided with a common

branch, means for impressing said modulated wave upon said demodulator, means for impressing an unmodulated carrier wave upon said demodulator, whereby the demodulator produces in the common branch 70 currents whose frequency is a combination of the modulating frequencies, and a signal controlled by the currents in said common branch.

2. In a signaling system, means for transmitting a carrier wave modulated by oscillations of two different frequencies, a receiving circuit therefor, a balanced demodulator associated with said receiving circuit and having a common branch tuned to a 75 frequency comprising a combination of the modulating frequencies, and a signaling device associated with said tuned circuit.

3. In a signaling system the combination 80 of a balanced demodulator having output circuits provided with a common branch, means for impressing upon the demodulator unmodulated carrier currents and carrier currents modulated in accordance with two different frequency currents whereby the demodulator produces in the common branch 85 currents whose frequency is a combination of the modulating frequencies, a rectifier coupled to the common branch to rectify the combination currents, and a signal controller responsive to the rectified currents.

4. In a signaling system, the combination 90 of a balanced demodulator having output circuits provided with a common branch, means for impressing upon the demodulator unmodulated carrier currents and carrier currents modulated in accordance with two different frequency currents whereby currents whose frequency is the difference of the modulating frequencies are produced 100 in the common branch, and a rectifier coupled to the common branch to rectify the difference frequency currents of the modulating currents.

5. In a signaling system, the combination 110 of a balanced demodulator having output circuits provided with a common branch, means for impressing upon the demodulator unmodulated carrier currents and carrier currents modulated in accordance with two different audio frequency currents whereby currents whose frequency is a combination of the modulating frequencies are produced in the common branch, means for tuning the common branch to the combination frequency currents, and a signal controller controlled by the combination frequency currents.

6. In a signaling system, the combination 115 of a balanced demodulator having output circuits provided with a common branch, means for impressing upon the demodulator unmodulated carrier currents and carrier currents modulated by two different frequency currents whereby currents whose fre- 120

65 130

quency is a combination of the modulating frequencies are produced in the common branch, and means to tune the common branch to the combination frequency currents.

7. In a signaling system, a balanced demodulator having output circuits provided with a common branch, means for impressing upon the demodulator unmodulated carrier currents and carrier currents modulated in accordance with two currents of different frequencies whereby currents whose frequency is the difference of the modulating frequencies are produced in the common branch, and means to tune the common branch to the difference frequency currents.

8. A signaling system comprising a low frequency line, a high frequency line, a carrier receiving channel between the low and high frequency lines, a balanced demodulator in the receiving channel, means for impressing upon the demodulator unmodulated carrier currents and carrier currents incoming over the high frequency line and modulated in accordance with two currents of different audio frequencies, whereby currents whose frequency is a combination of the modulating frequencies are produced by the demodulator, and means controlled by the combination frequency currents to impress currents of another frequency upon the low frequency line.

9. In a signaling system, the combination of a source of high frequency carrier currents, a source of carrier currents modulated by two currents of different lower frequencies, means including a demodulator upon which the unmodulated and modulated carrier currents are impressed to produce currents whose frequency is a combination of the modulating frequencies, means to rectify the combination frequency currents, and a

signaling element responsive to the rectified currents.

45

10. In combination, means for producing and transmitting a carrier wave simultaneously modified in accordance with a plurality of lower frequency waves, a receiving circuit therefor including a balanced demodulator having a common branch tuned to a frequency comprising a combination of said lower frequency waves, a calling device, and means controlled by the currents in said tuned branch to energize said calling device.

50

11. A telephone transmission system comprising means for producing and transmitting a carrier wave, apparatus for modulating said carrier wave in accordance with speech, a receiving station comprising means for receiving said carrier wave and demodulating it to reproduce the transmitted speech signal, means for impressing two different frequency waves well within the range of essential speech frequencies together upon said modulating apparatus during a non-talking period, and means connected to said demodulating apparatus responsive to a combination frequency wave of said two different frequency waves to produce a signal indication.

60

12. The method of calling in carrier wave transmission which comprises simultaneously modulating the transmitted carrier wave with two different frequency waves lying well within the range of essential speech frequencies, deriving from said modulated wave at a receiving station a wave of a combination frequency of said two different frequency waves and utilizing said derived wave to produce a ringing signal.

65

In witness whereof, I hereunto subscribe my name this 4th day of January A. D., 1923.

JOSEPH W. HORTON.
